UNITED STATES PATENT OFFICE.

AUTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

BREECH-BLOCK-ACTUATING GEAR FOR ORDNANCE.

1,074,842.

Specification of Letters Patent.

Patented Oct. 7, 1913.

Application filed August 11, 1911. Serial No. 643,573.

To all whom it may concern:

Be it known that we, Sir ARTHUR TREVOR DAWSON, knight, and GEORGE THOMAS BUCKHAM, both subjects of the King of 5 Great Britain, residing at Vickers House, Broadway, Westminster, in the county of London, England, have invented certain new and useful Improvements in Breech-Block-Actuating Gear for Ordnance, of 10 which the following is a specification.

This invention relates to breech block actuating gear for ordnance, particularly for guns of the semi-automatic type that can be readily converted into quick firing guns. 15 In guns of this kind the breech block is adapted to slide transversely across the breech opening by means of an actuating crank mounted on a spindle carried by the gun, the said spindle being provided at one 20 end with an external cam and at the other end with an actuating hand lever. When the gun is working semi-automatically the said cam is operated by a pawl hinged to the gun mounting so that during the return 25 movement of the gun after recoil the pawl actuates the cam and angularly displaces the spindle to move the block into the open position. It is retained in this position by the extractor until the latter is released in 30 introducing a fresh cartridge into the gun, whereupon the block moves into the closed position by the action of a spring. When the gun is acting as a quick firer, the said pawl is set into a position in which it cannot 35 actuate the said cam, and the aforesaid spindle is operated manually by the actuating hand lever. The said spring is generally arranged to act also as a buffer for the block and to cause it to slightly rebound when 40 opened in order to bring it into a position to prevent the cartridge case from becoming displaced when the gun is loaded at large angles of elevation.

According to our invention we provide 45 the actuating spindle at its end adjacent to the hand lever with a toothed segment which engages with a rack contained within a case or cavity forming part of the said hand lever. The said rack is under the influence 50 of a spring which is preferably of the helical type and bears at one end against the rack and at the other end against an adjustable plug or sleeve screwed into the outer end of the case. The end of the actuating spindle remote from that carrying

the toothed segment is provided with the cam for coöoperating with the hinged pawl in the usual manner.

According to a modification in order to enable the said spring to operate as a buffer 60 in opening the breech by hand and cause the block to rebound in opening so that the said block will serve as a cartridge retainer as is usual in this kind of breech mechanism, we employ a member carried by the spring 65 case which member controls the actuating spring and is adapted to engage with a fixed stop as the hand lever approaches the fully open position.

In order that the said invention may be 70 clearly understood and readily carried into effect we will describe the same more fully with reference to the accompanying drawings, in which:—

Figure 1 is an elevation, Fig. 2 a plan, 75 and Fig. 3 a section taken approximately on the line 1—1 of Fig. 1, showing one constructional form of the invention. Fig. 4 is an elevation and Fig. 5 a section taken approximately on the line 2—2 of Fig. 4, 80 showing a modified constructional form of the invention. Fig. 6 is a vertical section taken approximately along the axis of the actuating spindle of Fig. 1 or Fig. 4. Fig. 7 is a cross-section on the line 3—3 of Fig. 85 6 showing the cam. Fig. 8 is a side elevation, Fig. 9 a plan and Fig. 10 an end elevation showing the hinged pawl (which forms no part of our present invention) and the manner of setting the same into its inoperative position when the gun is working as a quick firer.

A is the breech end of the gun, B the breech actuating hand-lever, B' the spring case containing the actuating spring B^x, C 95 the block actuating spindle, C^x the toothed segment, C' the cam and D the hinged pawl adapted to engage therewith.

The spring case B' is made integral with the hand lever B, the handle B² of the latter 100 being provided with a spring catch b adapted to engage with a part of the gun when said hand lever is in the breech closed or closing position, the said hand lever being thereby restrained from moving until the 105 catch is released by grasping the handle of the hand lever as is well understood. The upper end of the spindle C carries the toothed segment C^x which engages with the short rack D' which is slidably mounted in 110

the case B'. The helical spring B^x bears at one end against the said rack and at the other against the end of the adjustable screwed plug b³.

5 When the gun is to work semi-automatically the aforesaid pawl D operates upon the cam C' on the actuating spindle C in the usual manner and as the hand lever B is restrained from moving by the catch b, the 10 actuating spindle C will revolve and, through the intervention of the toothed segment C^x, will move the rack D' in a direction to compress the spring B^x within the case B' that forms part of the hand lever B, as the 15 block assumes the open position. The return movement of the block is effected by the re-action of the spring B^x on the actuating spindle C through the rack D' and the toothed segment C^x. For the first round the 20 mechanism is opened by hand, the hand lever B² being then returned to its closed position in which the catch b engages with its pocket in the gun A. As the block is now held open by the extractors the spring B^x is 25 fully compressed ready to close the breech when the extractors are released by the action of loading.

When the gun is to work as a quick firer, the said pawl D is set into its inoperative 30 position relatively to the cam C' by any suitable means such as a change over switch comprising in the example shown by Figs. 8, 9 and 10 a transversely slotted rotary pin d having an operating arm d' at one end. 35 When this rotary pin is turned into a position in which the solid or unslotted portion lies against the pawl D the latter will be retained in a position in which it will not operatively engage with the cam C'. The 40 breech block can then be moved into its open position by the hand lever B and the connection existing between it and the actuating spindle C, through the spring case B', the rack D' and the toothed segment C^x, the said 45 rack occupying a position with its outer end abutting against the case B' as shown in Figs. 3 and 5. During the closing of the breech the pressure of the spring B^x maintains the rack D' in its relationship to the 50 pinion C^x and is of sufficient strength to rotate the spindle C and close the breech.

In the modification shown in Figs. 4 and 5, the spring case B' is provided with a two-armed lever B³ pivoted thereto. One arm b² 55 engages with a plunger b^{3x} which is loosely mounted in the adjustable threaded plug b³ and supports the rear end of the spring B^x. The other arm b⁴ has a projection b⁵ which is adapted to engage with a stop or depression b⁶ in the gun as the hand lever approaches the fully open position. The result of this engagement with the said depression b⁶ is to cause the spring B^x to become compressed by the arm b² acting on 65 the plunger b^{3x}, whereby the buffer effect is

obtained and the actuating spindle C caused to slightly move in the reverse direction to bring about a slight return movement of the block so that it can act to retain the cartridge in place during the loading operation 70 as aforesaid.

By means of our improvements the change from semi-automatic to quick fire is effected without the necessity of employing any change over gear (with the exception of 75 placing the hinged pawl out of action); furthermore when the gun is working as a quick firer the mechanism is not operated against the pressure of the actuating spring.

Although we have shown our invention 80 applied to a gun having a transversely sliding breech block, we wish it to be understood that we do not wish to limit ourselves to this type of gun, as our improvements are 85 equally applicable to breech screw mechanism working semi-automatically.

What we claim and desire to secure by Letters Patent of the United States is:—

1. In breech block actuating gear, the combination with the actuating spindle and 90 its hand lever, of a toothed member on said spindle, a reciprocatory spring controlled toothed member carried by the hand lever and gearing with the first-mentioned member.

2. In breech block actuating gear, the combination with the actuating spindle, and 95 its hand lever, of a toothed segment on the said spindle, and a spring controlled rack carried by the said hand lever and gearing with the toothed segment.

3. In breech block actuating gear, the combination with the actuating spindle, and 100 its hand lever, of a toothed segment on the said spindle, and a spring controlled rack contained in a cavity in the hand lever and gearing with the toothed segment.

4. In breech block actuating gear, the combination with the actuating spindle and 110 its hand lever, of a toothed segment on one end of the spindle, a cam on the other end of the spindle, an external pawl adapted to engage with said cam and a spring controlled rack carried by the said hand lever and gearing with the toothed segment.

5. In breech block actuating gear, the combination with the actuating spindle and 120 its hand lever, of a toothed segment on one end of the spindle, a cam on the other end of the spindle, an external pawl adapted to engage with said cam, and a spring controlled rack contained in a cavity in the hand lever and gearing with the toothed segment.

6. In breech block actuating gear, the combination with the actuating spindle and 125 its hand lever, of a toothed segment on one end of the spindle, a cam on the other end of the spindle, an external pawl adapted to engage with the said cam, a rack contained in 130

a cavity in the hand lever and gearing with the toothed segment, a plug closing the said cavity and a spring disposed between the said plug and the rack.

5 7. In breech block actuating gear, the combination with the actuating spindle and its hand lever, of a toothed segment on one end of the spindle, a cam on the other end of the spindle, an external pawl adapted to engage with said cam, a catch carried by the hand lever and adapted to engage with a part of the gun, a rack contained in a cavity in the hand lever and gearing with the toothed segment, a plug closing the said cavity and a spring disposed between the said plug and the rack.

8. In breech block actuating gear, the combination with the actuating spindle and its hand lever, of a toothed segment on the said spindle, a rack carried by the hand lever and gearing with the toothed segment, a spring controlling the said rack, a member

carried by the hand lever and coöperating with the spring, and a fixed stop with which the member engages as the hand lever approaches the fully open position. 25

9. In breech block actuating gear, the combination with the actuating spindle and its hand lever, of a toothed segment on the said spindle, a rack carried by the hand lever and gearing with the toothed segment, a spring controlling the said rack, a two armed lever carried by the hand lever, a plunger in contact with the spring and with one arm of the said lever and a fixed stop 30 with which the other arm of the lever is adapted to engage. 35

In testimony whereof we affix our signatures in presence of two witnesses.

ARTHUR TREVOR DAWSON.
GEORGE THOMAS BUCKHAM.
